UNITED STATES PATENT OFFICE.

JOHN HOWES BURTON, OF CEDARHURST, NEW YORK, ASSIGNOR TO THE GOVERNMENT
OF THE UNITED STATES.

DESIGN FOR A PENNANT.

52,865.

Specification for Design.

Patented Jan. 14, 1919.

Application filed September 19, 1918. Serial No. 254,873. Term of patent 3½ years.

To all whom it may concern:

Be it known that I, JOHN HOWES BURTON, a citizen of the United States, residing at Cedarhurst, Nassau county, Long Island, New York, have invented a new, original, and ornamental Design for Liberty-Loan Honor-Pennant, of which the following is a specification, reference being had to the accompanying drawing, forming part thereof.

The drawing shows in elevation a pennant embodying my new design. The pen-

nant is provided with a red border, a white field, four horizontal blue stripes across the field, and a percentage designation in red on the top of the white field portion.

I claim:

The ornamental design for a pennant as shown and described.

Signed by me at Washington, in the District of Columbia, this nineteenth day of September, 1918.

JOHN HOWES BURTON.
